Primary Examiner — Mark Goodwin(74) *Attorney, Agent, or Firm* — Brunet & Co.; Robert A. H. Brunet(57) **CLAIM**

The ornamental design for a ripper point, as shown and described.

DESCRIPTION

FIG. 1 is a front perspective view of the ripper point showing our new design;

FIG. 2 is a rear perspective view of the ripper point of FIG. 1;

FIG. 3 is a front view of the ripper point of FIG. 1;

FIG. 4 is a rear view of the ripper point of FIG. 1;

FIG. 5 is a side view of the ripper point of FIG. 1;

FIG. 6 is a side view of the ripper point of FIG. 1 from the opposite side as FIG. 5;

FIG. 7 is a top view of the ripper point of FIG. 1; and,

FIG. 8 is a bottom view of the ripper point of FIG. 1.

The shading lines in the Figures show contour and not surface ornamentation.
